UNITED STATES PATENT OFFICE

JAMES F. HUGHES, OF NEW YORK, N. Y.

MOUTHPIECE FOR CIGARETTES

Application filed May 18, 1931. Serial No. 538,379.

The present invention relates to mouth-pieces for cigars and cigarettes and consists in the combinations and arrangements of elements hereinafter described and particularly set forth in the accompanying claims.

The purpose of the invention is to provide a device which will keep the cigarette dry and effectively prevent the nicotine and tobacco fibres from entering the mouth and which will not offer any inconvenience or hindrance to the pleasure of smoking. The article is, furthermore, of the utmost simplicity and in its use is absolutely concealed from view.

A further object is in having the article of such structure that it may be incorporated into the body of the cigarette or cigar during manufacture, or may equally well be designed as a separate and independent device to be conveniently applied to the cigarette at the time of smoking and thereafter removed and again used with other cigarettes at will. It is further contemplated to produce an article of this character constructed of a single unitary piece and of such design that the same may be made in quantity production at small cost, to the end that the average smoker may have and carry several of the devices at all times ready for convenient use.

The devices shown herein are proposed as further improvements over the similar articles disclosed in my copending applications for U. S. Letters Patents, to wit:

"Attachment for cigarette" (Case "A") Serial No. 439,167; filed March 26, 1930.
 "Mouth-piece for cigarettes" (Case "B") Serial No. 469,167; filed July 19, 1930.
 "Mouth-piece for cigarettes" (Case "C") Serial No. 469,168; filed July 19, 1930.
 "Mouth-piece for cigarettes" (Case "D") Serial No. 501,446; filed Dec. 10, 1930.

The invention is shown by way of illustration in the accompanying drawings, wherein:

Figure 1 is a perspective view showing a cigarette with the article attached.

Figure 2 a similar view showing a modified construction of the device.

Figure 3 a longitudinal sectional view of the further modification.

Figure 4 a horizontal sectional view of Figure 3.

Figure 5 a detailed perspective view of the device shown in Figure 3.

Figure 6 a similar view of the device shown in Figure 2.

Figure 7 a transverse sectional view of a further modification.

Figure 8 a detailed perspective view of the article shown in Figure 7, and;

Figure 9 an end elevational view showing a further modification in the disc portion structure.

Referring to the construction in further detail and wherein the same reference characters designate corresponding parts in the different figures, 10 represents an ordinary cigarette to the end 11 of which is adapted to be attached the device shown herein. This end of the cigarette is in no way altered whether the device be incorporated in the cigarette when made or applied thereto as a separate attachment. The article may be of large or small size accordingly as the smoker desires to puff lightly or inhale deeply and fully, as will be understood.

At the end 11 of the cigarette is a disc-like piece 12 of relatively thin and non-inflammable material. Said disc-piece is formed with an integral portion or extension 13 of suitable length and having serrated edges 14 adapted to engage with the cigarette tobacco and hold the article in position when inserted as shown in Figure 1, and the end portion 15 of the member 13 is suitably pointed for convenient insertion and to avoid any mutilation of the cigarette body. It will be understood the article may be incorporated into the cigarette during the process of manufacture or separately attached thereto by the smoker and detached when the cigarette has been consumed.

The article, i. e. the disc portion 12 and penetrating prong 13, is preferably made from any suitable fibre or non-inflammable material and is so designed that the same may be produced in large quantities and at small cost.

In the construction shown in Figure 1 the prong or penetrating part 13 joins the disc portion 12 adjacent the end thereof and is slightly bent so as to enter the cigarette towards the center thereof when inserted as illustrated in Figure 3.

In the construction shown in Figures 2 and 6 the disc-portion 15^a is cut away as at 16 providing the prong portion 17 that centrally penetrates the cigarette tobacco as illustrated in Figure 2. In this design the side edges 14 of the prong portion are serrated as in Figures 1 and 5. The cut away portion 16 provides an appreciably wide opening for smoke to pass through the cigarette end, and this opening together with the several apertures 18 enables the device to function perfectly when in applied position. In like manner the disc 12 in Figure 1 is formed with a plurality of apertures 18.

In the construction shown in Figures 7 and 8 the prong portion 19 of the disc 20 is disposed at relatively right angles to said disc and penetrates the tobacco of the cigarette end 11 immediately adjacent the wrapper 21 thereof, as shown in Figure 7. In all other respects the construction of the article, its manner of attachment and use are the same as described in Figures 1 and 2.

30 In the arrangement shown in Figure 9 the disc 22 is cut at 16 as in Figure 6 to provide the tongue or prong (not shown) and in this instance the apertures or openings 23 and 24 are designed and arranged to simulate a human face.

It is to be understood the invention is not limited to the details of construction here shown and described, as these may be varied widely without departing from the scope of 40 the invention as defined by the claims.

What is claimed as new is:

1. A cigarette mouth-piece comprising a disc adapted to lie against the cigarette end and having an inwardly bent and integral 45 portion for penetrating the cigarette tobacco, said disc and penetrating portion being stamped from a fibrous sheet, substantially as set forth.

2. A cigarette mouth-piece comprising an 50 apertured disc of fibrous material having an integral and inwardly bent portion adapted to penetrate the tobacco and hold said disc member against the cigarette end, said inwardly bent portion having serrated edges 55 for the purpose set forth.

In testimony whereof I affix my signature.
JAMES F. HUGHES.
